W. B. C. Washburn INVENTOR.

BY *Arthur H. Knorr* ATTORNEYS.

UNITED STATES PATENT OFFICE.

WALTER BAILEY CHAFFIN WASHBURN, OF CANAJOHARIE, NEW YORK, ASSIGNOR TO BEECH-NUT PACKING COMPANY, OF CANAJOHARIE, NEW YORK, A CORPORATION OF NEW YORK.

DISTRIBUTING DEVICE.

Application filed August 19, 1927. Serial No. 214,026.

My invention relates to distributing devices and has for its object to provide a distributing device comprising a vertical channel adapted to properly support and deliver 5 cylindrical packages arranged in two vertical contacting columns; also to provide such a device with a folding flag adapted to be held in either a downwardly or an upwardly extending position.

10 The following is a description of a distributing device embodying my invention, reference being had to the accompanying drawings, in which,

15 Fig. 1 shows in perspective a distributing device embodying my invention;

Fig. 2 is an enlarged sectional view of the same on the line 2—2, Fig. 5;

Fig. 3 is a section of the same on the line 3—3, Fig. 1;

20 Fig. 4 shows a container constituting a part of my device with a cover partially broken away which may be applied thereto; and

Fig. 5 shows a portion of my device in section on the line 5—5, Fig. 2.

25 Referring more particularly to the drawings, 2 is a casing having side walls which extend downward and are fastened to a base portion 4. This base portion, as shown in Fig. 5, is at its forward end bent upwardly

30 so as to form a rearwardly inclined wall 6 and then downwardly so as to form an abutment 8 and then is curved and extended upwardly to a point 10 substantially at the middle of the side walls 2. It is then extended

35 substantially horizontally as at 12 and connected at 14 to a rear wall 16 integral with the side walls 2. The front edges of the side walls are provided with inwardly turned flanges 18 which extend to the tops of the side walls but stop at points 20 so as to leave a

40 discharge opening above the front portion of the bottom wall of the chute, of a height greater than one-half the depth of the chute but less than the full depth. Within the casing and through the upper end thereof is a removable container 22 having two layers of cylindrical packages 24 therein. This

45 container has secured to its upper end a flap or flag 26 which can be bent downward to the position shown in Fig. 4 or upward to the position shown in Fig. 1. When it is bent upward and the container is fully inserted within the casing, the side flanges 18 engage with the front lower portion thereof and hold it in

vertical position. The container can be inserted into the casing with the flag in the position shown in Fig. 4 if desired.

55 The end of the container opposite the flag 26 has its front portion 28 disconnected from the side walls as shown at 30 and is preferably in its medial part provided with a scored or weakening line 32.

60 When the container is inserted in the casing the packages in the front column rest upon this front portion 28 and hold it down against the metallic flooring so that it is supported thereby in the desired inclined position, as shown in Fig. 5. The front portion 28 is preferably bent outwardly along the line 32 before the container is inserted in the casing. 65 The forward part of the rear portion of the end wall of the container is supported by the abutment at the point 10 of the casing.

70 In using the device, the parts are assembled as shown in Fig. 1, the container being previously filled with round packages. The substantially horizontal portion 12 supports the rear column while the front column moves downwardly, the packages rolling out of the discharge opening until their movement is arrested by the abutment 8. The packages may be removed one or two at a time and as they are removed more packages roll downward from the front column until movement is arrested by the abutment. As the front 75 column moves downward the packages from the upper end of the rear column roll forward so that the two columns are maintained at approximately the same height.

80 The device constitutes an efficient means for delivering round packages in two vertical contacting columns and provides a visible flag for display and advertising purposes and embodies a container to which a cover may be applied so as to form a box for an advance supply from the packages to be distributed.

85 As will be evident to those skilled in the art, my invention permits various modifications without departing from the spirit thereof or the scope of the appended claims.

90 What I claim is:

95 1. In a distributing device, the combination of a vertical chute having inwardly turned forward edges and adapted to hold two columns of cylindrical packages, a discharge opening below the lower ends of said edges having a width less than the depth of said chute and greater than one-half of said depth,

a floor for said chute having a sloping portion extending beyond the front of said chute, and an abutment coacting with said floor and located in front of said chute at a distance 5 approximately equal to its depth, the rear portion of said floor being substantially horizontal.

2. A distributing device comprising a casing having a vertical channel composed of a 10 rear and side walls, the side walls having inwardly turned portions at their front edges and having an opening at which the lower ends of said inwardly turned portions terminate, an abutment spaced away forwardly 15 from said lower end, a floor extending in a downwardly slanting direction toward said

abutment, a container within said casing having the front portion of its lower wall disconnected from its side walls and downwardly inclined and a rear portion substantially horizontal, the inclined portion of said lower wall engaging said floor and being supported thereby in the desired inclined position, said floor having a projection engaging the forward part of said rear horizontal portion of the end wall of said container, and supporting the same.

In testimony whereof, I have signed my name to this specification this 17th day of August, 1927.

WALTER BAILEY CHAFFIN WASHBURN.
